UNITED STATES PATENT OFFICE.

ADA SCHNEIDER, OF CHICAGO, ILLINOIS.

ROUGE-HOLDER.

No. 911,270.

Specification of Letters Patent.

Patented Feb. 2, 1909.

Application filed June 10, 1908. Serial No. 437,631.

To all whom it may concern:

Be it known that I, ADA SCHNEIDER, a resident of Chicago, in the county of Cook and State of Illinois, have invented certain 5 new and useful Improvements in Rouge-Holders, of which the following is a full, clear, and exact description.

The invention relates to rouge-cloths or articles designed for ladies' use and the application of powder and rouge, and adapted 10 to be conveniently carried about the person.

In the use of rouge or rouge-containing devices, it is usually necessary to provide a wrapper or receptacle therefor, so that it 15 may be carried about the person so that the rouge or coloring material will not be applied to whatever it may come in contact with, *i. e.*, the rouge or rouge-containing article cannot be carried in a hand-bag or 20 elsewhere on the person without providing a wrapper or receptacle therefor, because the rouge would come in contact with the hand-bag.

The invention designs to provide an improved 25 rouge-holder which may be folded and conveniently carried in any of the usual places without providing a special receptacle therefor.

A further object of the invention is to 30 provide an improved rouge-cloth by which application of rouge may be made in such manner that the rouge will not be imparted to the fingers during its application.

The invention further designs to provide 35 an improved combined rouge and powder-cloth which may be conveniently carried without danger of coloring anything that it may come in contact with.

With these objects in view, the invention 40 consists in the several novel features hereinafter set forth and more particularly defined by claims at the conclusion hereof.

In the drawings: Figure 1 is a perspective 45 of a rouge-holder embodying the invention. Fig. 2 is a perspective of the improved holder showing it folded so it may be used for the application of powder. Fig. 3 is a perspective of the improved holder when folded so it may be conveniently carried about the person and so the coloring-matter and powder will be protected within 50 the folds thereof.

A denotes a piece of suitable cloth, such as flannel, which is usually of elliptical form 55 and which is impregnated with suitable coloring material, by saturation in a coloring

liquid. This cloth is stitched near its edge as at *a* to a suitable backing B, preferably of chamois. This backing is also usually elliptical in form or of larger area than the cloth A so that the margin *b* of the chamois will project outwardly beyond the margin or edge of the rouge-cloth. The cloth and backing are creased longitudinally and transversely as indicated at *c*, so that they 60 may be given two folds as shown in Figs. 2 and 3. Thus the impregnated cloth may be folded so that it will lie entirely within and be covered by the chamois backing, and furthermore, the projecting marginal portion 65 of the backing effectively protects the edges of the impregnated cloth from contact with anything when carried about the person. Furthermore, the impregnated cloth when folded as shown in Fig. 2 will be disposed so its face-portions will be folded upon each other and will not contact with the projecting marginal portion of the chamois. Therefore the marginal portion 70 will remain and may be used to wipe off any 75 excess of coloring matter after it has been applied.

It is sometimes desirable to utilize the device for the application of face-powder as well as rouge and the formation of the 85 article so that it may be given a double fold makes it possible to utilize a portion of the back-face of the chamois for the application of face-powder. When the holder has been given a single fold as shown in Fig. 2, 90 the central portion of the chamois may be used to hold face-powder so that it may be applied while the rouge-cloth lies wholly between the folds of the chamois and when the article is given another fold into position seen in Fig. 3 the face-powder on the chamois will be held between the folds of the chamois so that it may be conveniently carried wherever desired.

The invention thus provides an improved 100 rouge-holder which embodies a cloth which has been saturated in a coloring liquid and is adapted for application of the color as desired while the backing prevents contact of the cloth with the fingers or hands during 105 use of the rouge-cloth. The projecting marginal portion of the chamois protects the edges of the rouge-cloth so that they will not come in contact with the fingers in applying rouge or with anything when the cloth is 110 folded and may be used to wipe off or distribute the rouge when it has been applied.

from the cloth A. The article is foldable so that one portion of the backing may be used to hold the face-powder and furthermore it may be conveniently carried about a lady's person.

As a result of the use of a cloth which has been saturated in a liquid containing coloring matter and providing a protective backing for the saturated cloth all possibility of

10 losing the coloring matter is avoided and this feature is advantageous over a holder containing a rouge-powder in that the latter is more likely to fall out of a containing pocket or off of a surface on which it is held.

15 Having thus described the invention, what I claim as new and desire to secure by Letters Patent, is:

1. The combination of a cloth which has been saturated in a coloring liquid and a 20 protective backing to which the cloth is secured, the backing projecting outwardly from the edge of the cloth, the backing and cloth being foldable so that the cloth will lie between the folds of the backing.

2. The combination of a cloth which has 25 been saturated in a coloring liquid and a protective backing, the cloth and backing being stitched together and the backing having a projecting marginal portion extending outwardly from the edge of the cloth, and the 30 backing and cloth being foldable so that the cloth will lie between the folds of the backing.

3. The combination of a cloth which has been saturated in a coloring liquid and a 35 backing to which the cloth is secured having its margins extending outwardly beyond the edge of the cloth, said cloth and backing being foldable transversely and longitudinally so that a portion of the back-face of the 40 backing may be used to hold and apply face-powder and so that the powder holding portion will lie between the folds of the backing.

ADA SCHNEIDER.
